SUCKER ROD ELEVATING DEVICE

Filed Apr. 27, 1921

UNITED STATES PATENT OFFICE.

PICKETT G. KILDOW, OF IOWA PARK, TEXAS.

SUCKER-ROD-ELEVATING DEVICE.

Application filed April 27, 1921. Serial No. 465,013.

To all whom it may concern:

Be it known that I, PICKETT G. KILDOW, citizen of the United States, residing at Iowa Park, in the county of Wichita and State of Texas, have invented certain new and useful Improvements in Sucker-Rod-Elevating Devices, of which the following is a specification.

This invention relates to a sucker rod elevating device for deep well pumps, being particularly designed for use in connection with oil well pumps, and has as one of its principal objects to provide a device of this character wherein a sucker rod may be locked against displacement from the device to fall back into the well.

The invention has as a further object to provide a device wherein the latch employed will, when upward pull is exerted upon the device, be positively moved to closed position blocking disengagement of the sucker rod from the device.

And the invention has as a still further object to provide a device wherein, when the latch is shifted, said latch will be automatically locked in closed position so that even though upward pull upon the device is relieved, the latch will, nevertheless, be held to block disengagement of the sucker rod from the device.

Other and incidental objects will appear hereinafter.

In the drawing:

Figure 1 is a plan view showing the bail of the device swung to one side.

Figure 2 is a sectional view illustrating the locking member of the device in active position, and

Figure 3 is a transverse section on the line 3-3 of Figure 2, looking in the direction of the arrows.

In carrying the invention into effect, I employ a hook-shaped body member 10 having a slot 11 therein and formed on the end 45 of the shank of said body member is a trunnion 12. Threaded into the body member opposite said trunnion is a cap bolt 13 providing a second trunnion and swingingly connected with the body member by said 50 trunnions is a bail 14 having an eye 15 so that the usual swiveled hook of a cable may be readily connected with said bail. As particularly shown in Figure 1, the arm of the bail engaged with the cap bolt 13 is provided at its inner side with a beveled face 16.

Pivoted at a point between its ends upon the body member 10 at its upper side is a latch 17 and pivotally connected at one end to said latch is a pitman 18, the outer end portion of which is, as shown in Figure 3, enlarged to ride against the upper face of the body member and is slidably connected with said member by a pin 19 extending through a suitable slot in the pitman. At its outer end, the pitman is provided with a beveled face to coact with the beveled face 16 of the bail. Secured at one end to the forward end portion of the pitman is a coil spring 20 the opposite end of which is engaged with a hook 21 upon the body member. This spring acts upon the pitman for normally holding the latch 17 in open position, as shown in Figure 1, lying at one side of the slot 11 in the body member engaged at its outer end with a stop pin 22 upstanding from the bill of the body member. Formed in the bill of the body member at its upper side is a slot or recess 23 and secured at one end in said slot is a spring detent or locking member 24 projecting beyond the periphery of the body member so that said locking member may be readily grasped. As will be noted, the locking member 24 normally projects at its outer end portion above the upper face of the body member to coact with the latch 17 as shall be later explained, and is arranged to extend beneath the latch, when the latch is in open position, as shown in Figure 1, so that the latch may, without interference by the locking member, be swung across said member.

As is well known, the sucker rods of deep well pumps are composed of a plurality of sections, such as suggested in the drawing at 25, the sections being threaded together at their meeting ends. Near their ends, the sections are usually provided with squared portions and are further formed with terminal heads. The operation of disassembling a rod is accomplished by elevating the rod say for the length of one of its sections, when the section exposed at the top of the rod is unthreaded from the next adjacent section, the rod being then again elevated to expose the next section, and so on until all of the sections have been detached. Heretofore, considerable difficulty has been experienced with the ordinary elevating devices employed in that no means is provided for lock-

ing the sucker rod against accidental release. Consequently, it very often happens that in unthreading a section of the rod, the rod slips from the elevating device and falls back into the well. This, of course, not only occasions delay and danger but also involves considerable expense since it is then necessary to fish the rod out of the well. The present invention, accordingly, seeks to overcome these disadvantages. In operation, the bail 14 of the device is first swung to one side, as shown in Figure 1, when the body member is, as illustrated in Figure 3, engaged beneath the head of the uppermost section of the rod, the squared portion of the rod being received in the slot 11. Upward pull upon the bail for elevating the rod will then serve to swing the bail to a vertical position with respect to the body member so that the beveled face 16 of the bail will be caused to ride against the beveled outer end of the pitman 18 for shifting the pitman longitudinally and swinging the latch 17 to closed position behind the rod. As soon as the rear end of the latch rides over the locking member 24, this member will, as shown in Figure 2, spring upwardly behind the latch for automatically locking the latch closed. Thus, as will be seen, pull upon the device will initially serve to positively move the latch to closed position when the latch will then be locked closed so that even though upward strain upon the device is relieved, manipulation of the rod in the operation of detaching one of the sections cannot serve to cause disengagement of the rod from the device. However, when it is desired to release the device, the locking member 24 may, after the bail has been swung to one side, simply be depressed when the spring 20 will operate to immediately shift the latch to open position. I accordingly provide a highly efficient construction for the purpose set forth and a device which, in actual practice, will not only avoid the loss of a great deal of time

but will also effect a material saving in operating expense.

Having thus described the invention, what is claimed as new is:

1. A sucker rod elevating device including a body member, a latch thereon movable to closed position locking a rod in engagement with the body member, a bail connected with the body member, means whereby movement of the bail will shift the latch to closed position, and means on the body member independent of the bail and shifting means to lock the latch in closed position. 55

2. A sucker rod elevating device including a body member, a latch pivoted thereon and movable to closed position for locking a rod engaged with the body member, a pitman slidably mounted on the body member and connected to said latch, a bail pivotally connected with the body member and constructed to actuate said pitman whereby to shift the latch to closed position. 60

3. A sucker rod elevating device including a body member, a latch pivoted thereon and movable to closed position for locking a rod engaged with the body member, a pitman slidably mounted on the body member and connected to said latch, and a bail swingingly connected to the body member and provided with a beveled face bearing against the outer end of the pitman for shifting the latch to closed position. 70

4. A sucker rod elevating device including a body member, a latch pivoted thereon and movable to closed position for locking a rod engaged with the body member, a pitman connected to said latch, a bail swingingly connected to the body member and provided with a beveled face to coact with the pitman for shifting the latch to closed position, and a spring locking member movable into the path of the latch in the rear thereof for automatically locking the latch closed. 85

In testimony whereof I affix my signature. 90

PICKETT G. KILDOW. [L.S.]
